UNITED STATES PATENT OFFICE.

GEORGE Y. BOGART, OF FARMER VILLAGE, NEW YORK.

NECK-YOKE.

SPECIFICATION forming part of Letters Patent No. 242,255, dated May 31, 1881.

Application filed April 4, 1881. (Model.)

To all whom it may concern:

Be it known that I, GEORGE Y. BOGART, of Farmer Village, in the county of Seneca, and in the State of New York, have invented certain new and useful Improvements in Neck-Yokes; and I do hereby declare that the following is a full, clear, and exact description thereof, reference being had to the accompanying drawings, and to the letters of reference marked thereon, making a part of this specification.

This invention relates to certain improvements in neck-yokes for harness; and it has for its objects to provide an improved means of attaching the leather or pole-support to the neck-yoke bar, and these objects I attain by the devices illustrated in the accompanying drawings, in which—

Figure 1 represents a side elevation of my improvement; Fig. 2, a sectional view on the line *x x* of Fig. 1; Fig. 3, a detached view of one of the clasps or clips by which the leather is secured to the yoke, and Fig. 4 a detached view of a modification of the clasp or clip.

The letter A indicates the yoke, which is constructed in the usual manner, and B the leather or pole-support, which has the usual opening, C, for the purpose.

The letter D indicates the clips or clasps, which are formed of metal so as to partially encircle the yoke at each side of the shoulder E. The said clips are provided or formed with parallel lips F, which embrace the leather at its upper edge, and are secured thereto by means of the screw bolts and nuts G H.

The letter I indicates a metallic strap, through which the screw-bolts also pass, and by means of which the clasps are more securely connected.

The outer ends of the clips are closed by means of removable blocks K, or by a solid block permanently attached to or formed on one of the lips, the lips being united at these points by means of the pins L, as indicated. The said blocks are recessed on the inside, as indicated by the letter N, for the reception of the ends of a removable bar, M, which extends through a loop at the upper edge of the leather, by means of which the leather is held with the utmost security to the yoke and clips.

Having thus described my invention, what I claim, and desire to secure by Letters Patent, is—

1. The combination of the neck-yoke and the leather or pole-support, the clips or clasps partially encircling the yoke, and provided with lips which embrace the upper edge of the leather, the connecting-strap, and confining bolts and nuts, and the movable or attached blocks closing the outer ends of the clasps or clips, all substantially as and for the purposes specified.

2. The combination of the yoke-bar and clasps secured thereto and their lips, the recessed blocks confined or secured between the clasps or clips, the rod seated at its ends in the recessed blocks, and the leather, the whole arranged and secured together substantially in the manner specified.

In testimony that I claim the foregoing I have hereunto set my hand and seal this 21st day of March, 1881.

GEORGE Y. BOGART. [L. S.]
